(57) **CLAIM**

(**) Term: **14 Years**

(21) Appl. No.: **29/184,002**

The ornamental design for a insect trap that utilizes propane gas, as shown and described.

(22) Filed: **Jun. 19, 2003**

DESCRIPTION

(51) LOC (7) Cl. 22-06

FIG. 1 is a perspective view of an insect trap that utilizes propane gas, the design being characterized by a side-by-side arrangement of the propane tank with the insect trap.

(52) U.S. Cl. D22/122

FIG. 2 is a front view of the insect trap and propane tank shown in FIG. 1, the rear being a mirror image thereof;

(58) Field of Search D22/122, 120,

D22/119; 43/113, 112, 139, 132.1; 424/45

FIG. 3 is a left side view of same;

FIG. 4 is a right side view thereof;

FIG. 5 is a top view thereof;

FIG. 6 is a bottom view thereof; and,

FIG. 7 is a perspective view of the propane tank and insect trap without the environmental structures shown for clarity of disclosure.

The cover, cart, trap cup, the tank valve and controls are shown in dashed lines are not a part of this design.
